(57) **CLAIM**

The ornamental design for a stretching device, as shown and described.

DESCRIPTION

FIG. 1 is a perspective view of the stretching device showing my new design in a condition of use;

FIG. 2 is another perspective view thereof;

FIG. 3 is a left side view thereof;

FIG. 4 is a right side view thereof;

FIG. 5 is a top view thereof;

FIG. 6 is a rear view thereof; and,

FIG. 7 is a front view thereof.

The door, the wall, and the figure in the broken lines are for the purposes of illustrating environmental structure, which form no part of the claimed design. The broken lines shown on the stretching device are for the purposes of showing stitching, which form a part of the claimed design. The cross hatching shading in the figures is fragmentarily shown for convenience of illustration, it being understood that the cross-hatching shading is uniformly continued over the surface on which it appears.
